[57] CLAIM

The ornamental design for a chaise lounge, as shown and described.

DESCRIPTION

FIG. 1 is a front perspective view of a chaise lounge showing our new design;

FIG. 2 is a front elevational view;

FIG. 3 is a side elevational view, the opposite side being a mirror image thereof;

FIG. 4 is a rear elevational view; and

FIG. 5 is a top plan view thereof.

FIGS. 2 through 5 have been drawn to a smaller scale with respect to FIG. 1.
